U.S. Appl. No. 29/675,602, filed Jan. 3, 2019, Melissa Ann Kreuzer et al.

Primary Examiner — Deanna L Pratt*(74) Attorney, Agent, or Firm* — Alexandra S. Anoff(57) **CLAIM**

The ornamental design for a smart hub for a beauty regimen, as shown and described.

DESCRIPTION

FIG. 1 is a perspective view of a first embodiment of our new design for a smart hub for a beauty regimen;

FIG. 2 is a front elevation view thereof;

FIG. 3 is a left elevation view thereof;

FIG. 4 is a back elevation view thereof;

FIG. 5 is a right elevation view thereof;

FIG. 6 is a top plan view thereof; and,

FIG. 7 is a bottom plan view thereof.

The broken lines shown in the drawings are for illustrative purposes only and form no part of the claimed design.
